UNITED STATES PATENT OFFICE.

OLLIE B. NEWMAN, OF CAMP CHASE, OHIO.

BOX FILLER.

Application filed September 17, 1924. Serial No. 738,258.

To all whom it may concern:

Be it known that I, OLLIE B. NEWMAN, a citizen of the United States, residing at Camp Chase, in the county of Franklin and 5 State of Ohio, have invented new and useful Improvements in Box Fillers, of which the following is a specification.

The present invention is directed to improvements in devices for filling boxes with 10 ice cream or the like directly from the containers or cans.

The primary object of the invention is to provide a device of this character so constructed that a box for retailing ice cream 15 in quantities of one-half pint, pint or quart can be easily and quickly forced into a can containing ice cream and compactly filled without the aid of a spoon or dipper as is now the usual practice.

20 A further object of the invention is to provide a device of this character constructed in such manner that it can be conveniently mounted upon a cabinet containing ice cream cans in a position to force the 25 box into a selected can for filling the same for retail customers.

With these and other objects in view, this invention resides in the novel features of construction, formation, combination and 30 arrangement of parts to be hereinafter more fully described, claimed and illustrated in the accompanying drawing, in which:—

Figure 1 is a top plan view of the device.

Figure 2 is a side view.

35 Figure 3 is a sectional view on line 3—3 of Figure 2.

Figure 4 is a vertical sectional view through the box holder.

Figure 5 is a bottom view thereof.

40 Figure 6 is a detail sectional view of the rod adjusting means.

Referring to the drawing 1 designates an ice cabinet in which the usual ice cream containing cans 2 are placed and from which 45 cream is sold in small quantities. It is the usual practice to use a dipper or spoon for removing the cream from the can and packing the same in the boxes, but this requires considerable time and trouble and it is to 50 overcome this objection that the present invention has been perfected.

The cabinet in this instance has contained therein a pair of cans, but it will be of course understood that the device can be

used with equal success in connection with 55 one or more than two cans, said cabinet being provided with the usual top 3.

Suitably mounted upon the upper edge of the rear wall of the cabinet is a block 4, said block having rotatably secured thereto 60 a yoke 5 which pivotally supports the head 6. A pair of telescopically connected sections 7 are provided and serve to adjustably connect the head 6 to one end of the frame 8. To the other end of the frame is secured 65 one of the sections 9 of the handle 10, said sections being telescopically connected. Disposed between the side bars of the frame 8 and pivotally connected thereto is a sleeve 11 and carried by said sleeve is a tubular 70 extension 12 in which is slidably mounted a locking bolt 13. This bolt has a groove 14 therein and in which is engaged a pin 15 carried by the extension 12.

The extension is provided with a head 75 16 provided with an inclined surface 17 and further has swivelly connected to its outer end a handle 18 provided with a rib 19 adapted to co-act with the surface 17 to withdraw the bolt when the handle is rotated, the pin 15 preventing the bolt from rotating. The bolt is normally held in its operative position by the coil spring 21, and has its inner end provided with a jaw 20, the purpose of which will appear later. 85

Slidably engaged in the sleeve 11 is a shaft 22 provided throughout its length with annular grooves 23 and which co-operate with the jaw 20 to hold the shaft interlocked with the sleeve in selected positions. 90 The lower end of the shaft has secured thereto a disk 24 having a pair of diametrically opposed pins 25 on its periphery for detachable engagement with the bayonet slots 26 formed in the box holder 27. This 95 holder is formed from suitable metal and receives and holds the cardboard boxes 28 of varying capacities. In order to permit the holder to readily enter the frozen cream in the cans 2 the lower edge thereof is provided with a cutting edge 29 and a resultant shoulder 30 upon which the open end of the box 28 rests.

Slidable in the shaft 22 is a rod 31, the lower end of which has fixed thereto a disk 105 32 adapted to engage the inverted bottom of the box 28 to hold the same against upward movement in the holder when the

same is being forced into the cream. The upper end of this rod is provided with a pin 33 adapted to selectively engage the notches 34 formed in the casing 35, said notches opening into the vertical slot 36 formed in said casing. The casing is suitably fixed upon the upper end of the shaft 22. In the drawing the disk 32 is shown engaged with the bottom of a box of one-half 10 pint capacity and at which time the pin 33 is engaged in the lowermost notch 34. When it is desired to fill a pint box the pin 33 is engaged in the uppermost notch and when a quart box is being filled the pin engages the upper wall of the slot 36. In this manner the disk 32 can be easily and quickly 15 adjusted to cooperate with boxes of varying capacities.

A wire strand 37 is carried by the lower 20 end of the holder 27 and is so arranged as to cross, as at 38, said wire serving, when the holder is rotated to sever the cream even with the open end of the box 28. To rotate the holder 27 a cross handle 39 is connected 25 to the lower end of the casing 35.

To prevent the cream can 2 from turning with the holder 27, a clamp 40 is engaged therewith, said clamp being adjustably connected with a post 41 fixed to the under 30 surface of the top 3.

In use, a box of the desired capacity is placed within the holder 27 in an inverted position and the rod 31 adjusted so that the disk 32 rests upon the bottom of the 35 box to hold the rim thereof upon the shoulder 30, whereupon the shaft 22 is interlocked with the sleeve 11 by the bolt 13, and upon swinging the handle 10 downwardly the holder will be forced into the 40 frozen cream, thus filling the box. The shaft is then rotated to cause the wire 37 to sever the cream evenly with the rim of the box and the handle is then swung upwardly a sufficient distance to permit the 45 holder 27 to be disengaged from the disk 24 and upon inverting the holder the box 28 can be conveniently removed therefrom.

By telescopically connecting the sections 7 of the frame 8 will be permitted to be adjusted 50 to positions to suit the positions of the cans 2 so that the device can be used in connection with cabinets of various sizes, the construction also permitting the frame to be swung freely to different positions.

The handle 10 being formed from telescopically connected sections different leverages can be obtained. Since the sleeve 11 is 55 adjustably connected with the shaft 22 it will be obvious that they may be relatively adjusted as the cream is removed from the cans 2, and when the device is not in use the holder 27 can be lifted from the cans and placed in a container filled with water.

A ring 42 frictionally engages around the 60 upper end of the holder 27 and is capable

of being slid downwardly thereon to scrape off any cream which may adhere thereto.

What is claimed is:—

1. A device of the class described, comprising a frame, a sleeve adjustably connected with the frame, means for adjustably mounting the frame upon an ice cream containing cabinet, a shaft engaged in the sleeve, means for adjustably interlocking the sleeve with the shaft, and a box holder 75 connected with the shaft, as and for the purpose set forth.

2. A device of the class described, comprising a box holder, a shaft detachably connected with the holder, said shaft being 80 adapted to be adjustably mounted upon an ice cream containing cabinet, a rod slidable in the shaft and having a disk upon its lower end for movement in the box holder, a casing carried by the upper end of the 85 shaft, and means carried by the rod for cooperation with the casing to hold the rod, and thus the disk in selected adjusted positions, as and for the purpose set forth.

3. A device of the class described, comprising a frame, telescopically connected sections adapted to adjustably connect the frame to an ice cream containing cabinet, a hollow shaft adjustably connected with the frame and having a box holder detachably 95 connected to its lower end, a rod slidable in the shaft and having a disk upon its lower end adapted to engage a box mounted in the holder, a casing mounted upon the upper end of the shaft, said casing having 100 notches formed therein, a pin carried by the rod for selectively engaging the notches to hold the disk in adjusted positions to engage boxes of varying capacities mounted in the box holder.

4. A device of the class described, comprising a shaft adapted to be adjustably mounted upon an ice cream containing cabinet, a box holder carried by the shaft 110 adapted to hold a box, a rod mounted in the shaft and having a disk fixed to its lower end for engaging the box in the holder to prevent upward movement thereof in the holder when the holder is forced into a body of ice cream, and means for adjusting the rod for engagement with boxes of varying capacities.

5. A device of the class described, comprising a shaft adapted to be mounted upon an ice cream containing cabinet, a box holder removably connected with the shaft, a frame adjustably connected with the shaft, means for pivotally and adjustably connecting the frame with the cabinet, and a handle 120 for operating the frame to force the holder into an ice cream can contained in the cabinet.

In testimony whereof I have hereunto set my hand.

OLLIE B. NEWMAN.
